UNITED STATES PATENT OFFICE.

ERNEST A. FALLER, OF NEW YORK, N. Y., ASSIGNOR TO THE NORTH ELECTRIC COMPANY,
OF CLEVELAND, OHIO, A CORPORATION OF OHIO.

ELECTRICAL SELECTOR.

No. 927,455.

Specification of Letters Patent.

Patented July 6, 1909.

Application filed April 8, 1904. Serial No. 202,262.

To all whom it may concern:

Be it known that I, ERNEST AUGUST FALLER, a citizen of the German Empire, residing in New York, in the county of New York and State of New York, have invented a new and useful Electrical Selector, of which the following is a specification.

The present invention relates to apparatus or devices for establishing a regular order of 10 electrical actuations caused by an entirely irregular order of initiating acts.

One mode of application of the present invention is, for instance, in connection with telephone systems, in which the signals of 15 the calling subscribers are received at the exchange in an arbitrary irregular order, while it is desirable to arrange the same in a regular order or sequence for the purpose of establishing connection with the called subscribers.

For this purpose the invention consists of 20 the construction and arrangement of parts, mechanical and electrical, and of the electrical circuits hereinafter set forth, which in a general way comprise initiating or calling 25 devices at the sender stations, actuating or translating devices, intermediary circuit establishing means and controlling devices for the latter. All the devices with the exception 30 of the sending apparatus are preferably located at a central station, such as a telephone exchange, the sending apparatus however, may be located at places distant from the central station.

It will be seen that the apparatus herein 35 described and illustrated is adapted to a decimal system.

An entire number of one hundred lines entering a central station is divided into groups of ten terminals. Each group of ten terminals 40 of the isolator, is represented at the group selector by one row of contact points and controlled by one group selector magnet. The function of one of these magnets is to place, for the time being, the entire central 45 station under the control of one group of ten of the terminals. When this group of ten has been selected, the individual selector selects one terminal in the group and, for the time being, places the entire central station 50 under the control of this individual terminal. The individual translating device is now operated, whereafter the entire system reverts to common use.

It is old in the art to select a line by means 55 of a traveling contact finding a stationary

contact which latter is in a condition other than normal, but in this case the traveling contact was caused to stop and to interrupt its movement by its own act of finding a line. Devices for this general purpose are 60 known in the art as line finders and are employed for instance, in electrical gas cut outs such as the automatic electric circuit opener, U. S. Patent No. 279,023, patented June 5, 1883, and in automatic telephone systems, 65 such as described and claimed in the U. S. Patent No. 686,892, patented November 19, 1901. One of the essential differences between devices of this character and the present invention consists in the fact that in the 70 former the traveling contact forms part of a circuit over which the controlling electro-magnet is energized, which is not the case in the present invention. If such a line finder is intended for one hundred lines, its speed 75 cannot be much more than fifteen revolutions per minute, for the reason that the contact between the traveling contact and the stationary contact must be of sufficient duration to enable the controlling electro-magnet 80 to attract its armature before the contact is again broken.

It is obvious that the time of operation including the interval between two successive operations may vary from one twentieth 85 of one second to four seconds, averaging a consumption of time of two seconds per operation. In the present invention, however, in which the traveling contact does not form part of a circuit over which the controlling 90 magnet is energized, this space of time is eliminated, as the actuation of the controlling magnet is not depending upon the traveling contact maker and the contacts are entirely at rest during the time of performing 95 their useful function.

It will be seen, that in the present invention, the speed of operation of the normally rotating contact maker is only limited by the mechanical strength of the co-operating parts 100 and the required safety. In the apparatus illustrated, the speed of the normally rotating trailer arm is 400 revolutions per minute, a speed entirely impracticable in any of the machines heretofore in use. In the present 105 invention, the stopping of the traveling contact is not caused by its own act of finding a line, but by a prior operation beyond the control of the traveling contact and independent thereof. This is thought to be 110

- broadly new, as is also the herein described division of an entire selecting act into more than one specific selecting acts, one of them selecting one group out of a plurality of 5 groups of circuits and rendering the other groups for a time inoperative, and the other selecting one of the components of the selected group and rendering for a time all other components of said group inoperative.
- 10 In this manner the final circuit is selected by what might be termed a process of elimination. It is obvious, of course, that this arrangement is not limited to the use of a decimal system nor to only two selecting acts,
- 15 but any desired division into groups may be applied and any desired number of selecting acts may be resorted to without departing from the intended spirit and scope of the present invention.
- 20 In the drawings accompanying the present application for Letters Patent and forming a part thereof, Figures 1 and 2 are diagrammatic views illustrating the circuit selecting devices and their connections; Fig. 3 is a 25 detailed diagrammatic view of the complete circuit of one line when continued to its translating device, and Fig. 4 is a detailed view of a mechanical device at the central station capable of being acted upon by an 30 individual translating device belonging to a line.
- The entire central apparatus may be divided into four parts. The isolator, the group selector, the individual selector and 35 the translator or actuator.
- The isolator consists of a series of terminals, one for each of the lines ending at the central station. The terminals are preferably in the shape of clips 2 and are arranged 40 in groups of ten, each terminal in the group connected to one of the lines leading into the station, and each group having an eleventh clip 4 connected to battery and ground as hereinafter more fully will appear.
- 45 The isolator comprises on a suitable frame, the isolator bar 6, slidably supported by pins or bolts and provided with a series of isolator blades 7 secured to the bar 6 and resting on non-conducting material so that the blades 7 are capable of normally bridging all eleven 50 clips 2 forming one group. The isolator bar 6, is capable of lateral movement by means of a bell crank lever 8 held under tension of a spring 9 by a detent 10 which latter forms 55 the armature of an isolator magnet 11 connected by a conductor 12 to a battery ring 18 of the group selector and to battery and ground. Each of the isolator clips 2 is connected by a conductor 3 to a contact point 19 60 on the group selector of the apparatus. The contact points belonging to the same group are arranged in radial lines around the axis of the shaft 20. Each group of contact points 19 is provided with a group selector magnet 13 65 connected by means of a conductor 5 to the

eleventh or ground clip 4 of the isolator and on the other hand by a second conductor to a battery ring 17 which in turn is connected by conductor 45 to the main switch 35 and through battery 36 to ground. Each one of 70 the group selector magnets 13 is provided with an armature 14 acting as a detent for a stop 15, the latter capable of dropping into the path of a trailer arm 21, so that this trailer arm 21 which is normally rotating on 75 the shaft 20 to which it is frictionally secured, may stop on that row of contact points 19 which belongs to the energized group selector magnet 13.

In each row of contact pins 19 in the group 80 selector, ten of the contact pins are connected to the corresponding clips 2 of the isolator by means of the conductors 3 as hereinbefore stated, and the eleventh contact points 26 located nearest to the center are connected, 85 respectively, by conductors 27 to groups of translating devices 28 of the actuator, as hereinafter will be more fully described.

The trailer arm 21 consists of two series of trailer brushes, an outer series 23 capable of 90 making contact with the contact points 19, and the innermost trailer brush of this series capable of making contact with the contact points 26, and a second series 24 of contact brushes arranged to slide upon a corresponding 95 series of conducting rings 25, each of the conducting rings connected by a conductor 29 to the individual selector as hereinafter will be more fully described. The brushes of the outer series 23 and the inner series 24 are 100 connected in pairs, respectively, the outermost brush of the series 23 to the innermost brush of the series 24 and so on. The brush capable of making contact with the innermost contact points 26 of the rows of contact 105 points 19 of the group selector is connected to the outermost contact brush of the inner series 24 which glides on a ring 46, the latter being connected by means of the conductor 47 to ground. Each of the stops 15 is ar- 110 ranged to make contact with contact points 16, the stop 15 is electrically connected to the battery ring 17, to which also, as hereinbefore stated, the magnet 13 is connected and the contact point 16 is connected to the outer 115 ring 18 of the group selector and by means of a conductor 12 through the isolator magnet 11 to ground.

The construction of the individual selector Fig. 2 of the drawings, is very similar to the 120 construction of the group selector. This individual selector consists of a series of magnets 30, each of which is connected by means of a conductor 29 to one of the rings 25 of the group selector Fig. 1, the other wire of the 125 magnet leading to a battery ring 33 which by means of a conductor 34 is connected to the main switch 35 and through battery 36 to ground. Each of the magnets 30 is provided with an armature 31 acting as a detent 130

for the stops 32 which latter are capable of dropping into the path of a normally rotating trailer arm 38 of the individual selector. The trailer arm 38 is frictionally secured to a 5 constantly rotating shaft 37 and is provided with two trailer brushes 39 and 40. The inner trailer brush 39 glides on a ring 41 connected by means of a conductor 42 to the main switch 35 and through battery 36 to 10 ground. The outer trailer brush 40 is capable of making contact in succession with contact points 43, each of which is connected by means of a conductor 44 to one of a number of translating devices 28 of the 15 actuating device. Both trailer arms 21 and 38 are driven by a common power-device and may frictionally be secured to constantly rotating separate shafts 20 and 37, or to one common shaft. Each selector may also be 20 provided with a dial having numbers or other characters and each trailer arm with an indicator, such as the hand 22, Fig. 1, so as to indicate the group on the selector and the component of this group on the individual 25 selector, which for the time being control the operation of the central station.

From the foregoing description, it will be seen that the lines or circuits entering the isolator from the outside, are divided into 30 groups, and that the normal course of these circuits is from the clips 2 and 4 of each group through the respective magnets 13, to ground through battery; the magnet 13 of each group being common to all the circuits of 35 that group. It will further be seen that the wires 3 constitute parts of circuits branching at the clips 2 in groups from the respective groups of grounded circuits entering said clips; that these branch circuits are normally 40 open; that they may be partially closed in groups by the normally rotating contact brushes of the group selector; that this selector includes primary controlling devices (the magnets 13 and their detents) one for each 45 of the groups of main circuits entering the isolator; that a secondary circuit closing device comprising the individual selector acts to completely close any one of the partially closed branch circuits, and that all the 50 circuits entering the apparatus, save the one selected, are rendered temporarily inoperative after the selection of said circuit, by having their continuity interrupted by the isolator, as described.

55 It will be understood that the parts indicated by the reference numeral 28 and hereinbefore referred to as "translating devices", may be used for a variety of purposes; but in order to show an application of the present invention, I have selected as an illustrative case the one in which these translating devices are in the form of electro-magnets forming parts of an automatic telephone exchange switching apparatus, which apparatus, outside of said translating devices, is not

herein claimed as a part of the present invention:

Such automatic switching apparatus as I have herein shown, for the purpose above stated, may comprise, among other parts, a 70 clutch magnet 49 connected by conductors 48 in series with conductor 42, the latter connecting to the inner ring 41 of the individual selector at one end and at the other to conductor 34 at point 42', (see Fig. 2). This 75 magnet 49 is provided with a pivoted armature 50 acting as a detent for the bell-crank lever 51.

A constantly rotating shaft 53 is provided with a ratchet 54 fast thereon, adapted to be 80 engaged by a pawl 52 carried by a disk 55 loosely mounted on the shaft 53. The hooked end of the lever 52 has a tendency to engage a tooth of the ratchet wheel 54 under the influence of a spring 55'. This tendency is 85 opposed by the engagement of the opposite rounded end of the lever 52 with the end of the bell-crank lever 51. The strength of the spring 55' is so proportioned that it will overcome the tension of a spring 51' which holds 90 the lever 51 against its stop. Obviously as long as the lever 51 is held in its position of rest by the catch of the armature 50, the hooked end of the lever 52 cannot engage any 95 of the teeth of the ratchet 54. But as soon as the lever 51 is released from engagement with the catch of armature 50, the spring 55' will overcome the tension of the spring 51'; the hook of the lever 52 will engage a tooth 100 of the ratchet 54, and the latter being fast on the constantly rotating shaft, will carry the lever 52 around with the same. The rounded end of lever 52 then breaks engagement with the end of the lever 51, whereupon the spring 51' will return the latter to its 105 position of rest.

Secured to the disk 55 or to a sleeve carrying the same, is a cam 56. When the clutch magnet 49 becomes energized, it attracts its armature 50, releases the bell crank 110 lever 51 and the pawl 52 as above described. The latter engages with one of the teeth of the ratchet 54 which then causes the rotation of the disk 55 and the cam 56. The impulses energizing the magnet 49 are of very short 115 duration, and the armature 50, therefore, is immediately released and engages and holds again the spring controlled bell crank 51. After one revolution of the cam 56, the outer end of the pawl 52 strikes against the bell 120 crank lever 51, becomes disengaged from the ratchet 54 and the disk 55 with the cam 56 is brought again to normal rest.

The cam 56 Figs. 3 and 4, is so arranged 125 that it normally depresses a roller 57 secured to a rod 58, which latter is slidable in suitable bearings. Secured to the rod 58 is a lug 59 which by means of a rope, wire or belt, is connected to a weight 60. The tendency of this weight is to lift the rod 58 but is normally 130

prevented from accomplishing this by the cam 56, and only when the cam 56 rotates, is the weight 60 allowed to lift the rod 58.

The lug 59 carries a lifter 61 which consists essentially of a plate, an end view of which is shown in the drawings, provided with an upturned edge adapted to engage at times levers of a row of terminal shuttles presently to be described. The lug 59 also carries a stop-lever plate 62 normally pressed forward by a spring 70. At one end of this stop-lever plate is a stop lug 62', which, under conditions hereinafter described, is adapted to engage the teeth of a stationary rack 64. Located in a row in front of and substantially parallel to the stop lever plate 62 are the terminal shuttles one for each subscriber's line entering the switch-board. These terminal shuttles correspond in function to the horizontally movable terminal carriages of the exchange shown and described in U. S. Patent No. 686,892, herein before referred to and comprise each a metal sleeve 71 slideable vertically on a metal rod 68 and carrying a contact spring 65 in electrical connection therewith. Each of these contact springs has at its bottom end an outwardly turned toe to the bottom of which is secured a catch which latter is arranged to engage, under conditions hereinafter described, a detent 81 pivoted to the sleeve 71 and having an extension adapted to engage a stop 82. Each of these shuttles carries also a lever 63 fulcrumed thereto, having each a curved upper end adapted to engage the stop-lever plate 62, under the tension of a spring 69 also carried by the sleeve 71. Each of these levers 63 is also provided with a catch lug 63' for engagement with the upturned edge of the lifter 61. The lower end of each of the levers 63 forms an armature for an electro-magnet 28, there being one such magnet for each lever. These magnets constitute in this case the translating devices hereinbefore referred to.

Arranged in a row in front of the shuttles are a series of contact springs 66, each connected to a separate terminal clip 2 and each normally engaging the toe of a shuttle spring 65 when that shuttle is not in use. Also arranged in a row transversely of said shuttles are a plurality of superposed cord circuit terminal rods or bus bars 67 forming the electrical connecting means between a calling 55 and called subscriber's shuttle.

In order to prevent more than one terminal carriage spring 65 to make contact with a rod 67, the armature lever 63 and the stop-lever plate 62 operate as follows: The terminal rods 68 are all in one plane as also the upper ends of the armature levers 63. The lifter 61 and the stop-lever plate 62 are in the form of bars of substantially the length of the entire row of terminal rods 68, and are capa-

ble of placing any one of the terminal shuttle springs 65 into contact with any one of the rods 67 in the following manner: All armature levers 63 are normally resting against the front side of the stop-lever plate 62 as illustrated in Fig. 3, of the drawings. When an armature lever 63 is attracted by its electro-magnet 28, the upper end of the lever is removed from the front side of the stop lever plate 62 and this plate in being lifted by the weight 60 will glide off the rest of the armature levers and fall forward onto the upper end of the attracted armature lever. Its stopping edge is thereby placed into the plane of the stopping teeth 64, is engaged by the lowermost of these teeth and the stop lever plate 62 will thereby be stopped and the contact spring 65 of the terminal shuttle be brought in contact with the first bar 67, all of which takes place during one complete revolution of the cam 56. In case a second shuttle should be displaced, its armature would be attracted by its magnet 28, and when the stop plate 62 is lifted, it will not glide off the rest of the armature levers and fall forward onto the upper end of the attracted armature lever, but would rest against the upper end of the armature lever of the already displaced shuttle from which it would glide off in the further lifting process and its stopping edge placed into the plane of the stopping teeth 64 where it would be engaged by the second stopping tooth and made to stop so that the contact spring 65 of the second terminal shuttle is brought in contact with the second bar 67. This mode of operation is repeated with every shuttle until a shuttle has been connected to each of the rods 67.

The devices for resetting the terminal carriages are illustrated in Figs. 3 and 4, and consist of insulated resetting plungers 80, one for each cord-circuit bar 67, and a detent 81 on each terminal carriage. When the plunger 80 has pushed back the spring 65, the latter is engaged by the detent 81, the terminal carriage drops by gravity and when it reaches its position of rest, the rear end of the detent 81 strikes the pin 82, and the detent releases again the spring 65, so that when the terminal carriage is lifted, it may again engage with one of the cord circuit terminal rods 67. The plunger 80 may be operated by any suitable means. Such means however, is beyond the scope of the present invention. The stops 15 and 32 are set by rotating the rings 18 and 33 by means of levers attached to the lugs 76 and 79. Any suitable means for giving reciprocating motion at the proper time to these levers may be employed. The periphery of the rings 18 and 33 is provided with lugs 74 and 77, one for each stop 15 and 32, engaging the fingers 75 and 78 on those stops. The detents 14 and 31 under the tension of suitable

spring engage again the stops 15 and 32, and retain the same, so that the trailer arms 21 and 38 may resume their normal rotation.

Operation: When in the operation of this apparatus ground is placed on the sender 1 of a subscriber's station and the number of the calling line is, for instance, No. 49, as illustrated in the drawings, a circuit is established as follows:—from ground at the sending station over the line to the central station, to one of the springs 66, over conductor 73 to the first isolator clip 2 of the fifth group from the left hand side of the groups of isolator clips, illustrated in Fig. 1, from the isolator blade 7 normally in contact with all the clips of the group, to the lower clip 4 of this group, one of the conductors 5 to one of the group selector magnets 13, to the battery ring 17 of the group selector, over the conductor 45 to the main switch 35, through the battery 36, and to ground at the central station. The effect of this current will be the energization of the magnet 13 representing the group containing the lines No. 40 to 49 which in attracting its armature 14 removes the detent from the stop 15 and allows the latter to fall inward into the path of the outer end of the trailer arm 21 of the group selector. When the stop 15 is released by the detent on the armature 14, it closes a circuit as follows:—from ground at the central station to the isolator magnet 11, see Fig. 1, over conductor 12 to the outer battery ring 18 of the group selector, the back contact 16 of the stop 15, the stop 15 to the inner battery ring 17, over conductor 45 to main switch 35, see Fig. 2 of the drawings, through battery 36 to ground. The energization of the magnet 11 by this current results in the attraction of its armature 10, the removal of the detent of this armature from the bell crank 8, the vertical arm of which under the tension of the spring 9 moves toward the left, see Fig. 1 of the drawings, and removes the isolator blades 7 from the groups of isolator clips 2, making it impossible, for the time being, for any one to send in a call into the central apparatus. The normally rotating trailer arm 21 is now stopped by one of the stops 15, its indicator hand 22 pointing in the chosen example to the numeral 4, its outer series of trailer brushes resting on the contact points 19, the contact point 26 of this group, and the inner series on rings 46 and 25. A circuit is thereby closed as follows:—from ground at the sender 1 to the individual clip No. 49, that is the uppermost clip in the fifth row from the left hand side of Fig. 1 of the drawings, one of the conductors 3 to the tenth contact point 19 of the group selector, the trailer brush of the outer series 23 now in contact therewith, the second trailer brush of the inner series 24 of

the outermost of the rings 25, one of the conductors 29 to one of the magnets 30 of the individual selector, and representing the unit digit of the calling No. 49, to the battery ring 33 of this selector, the conductor 70 34 to the main switch 35 and through battery 36 to ground. The effect of this current is to attract the armature 31 of the magnet 30, remove its detent from the stop 32 which thereby drops into the path of the outer end of the trailer arm 38 of the individual selector, and causes the same to interrupt its revolution and to stop with its trailer brush 40 on the contact point 43 representing the number 9 and with its inner brush on the battery ring 41. A circuit has now been established as follows:—from the left hand side of the battery 36, Fig. 2 of the drawings, to the left bar of the main switch 35, conductor 34, conductor 42, wire joint 42' to the battery ring 41 of the individual selector, the trailer brush 39 of the trailer arm 38, the outer trailer brush 40, one of the contact points 43, one of the conductors 44, to one of the individual translating devices or electromagnets 28 in the actuator, and in the chosen example to the lowest electromagnet 28 of the fifth group from below, on the right hand side of Fig. 2 of the drawings, over one of the conductors 27, to one of the contact points 26 of the group No. 4 of the group selector, to the trailer brush of the outer series of brushes 23 of the trailer arm 21 now in contact therewith, the outermost of the trailer brushes of the inner series 24 100 of brushes of the trailer arm 21 resting upon the ring 46, the conductor 47 to the right hand blade of the main switch 35 and to the right hand side of the battery 36. The effect of this current in the present case is to 105 actuate the translating device 28. Having illustrated the translating device in the present case as an electro-magnet, it will result in the energization of this electromagnet 28, representing the calling or sending station No. 49.

Simultaneously with the energization of the magnet No. 49 of the groups of translating devices or electro-magnets 28, the clutch magnet 49 which is connected to the conductor 42 by means of the conductors 48, is energized, has attracted its armature 50 and has released the detent 51, whereby the pawl 52 is also released and drops into one of the teeth of the ratchet 54. The ratchet 54 is 120 secured to the shaft 53 constantly rotating with it. The dropping of the pawl 52 into one of the teeth of the constantly rotating ratchet 54 results in one complete revolution of the cam 56 and in an up and down movement of the rod 58 under the pull of the weight 60 as hereinbefore described. One of the magnets 28 having been energized and having attracted its armature lever 63, the 125 upward movement of the rod 58 and the 130

lifter 61 will cause the breaking of the connection between the stationary spring 66 and the spring 65 of the terminal-carriage of the calling line and will bring this terminal carriage into contact with one of the idle cord-circuit bars or rods 67 determined by the shoulder 83 of the stop lever 62 which prevents the stop lever to tilt forward until the bent upper ends of priorly displaced armature levers 63 are passed.

10 What is claimed as new and useful and desired to be secured by Letters Patent of the United States is:—

15 1. A progressive contact-maker comprising contact points divided into groups or sets, a normally rotating trailer-arm adapted to make contact with multiple contact points of one group at one time, means for interrupting the rotation of the trailer arm, and 20 means for controlling the interrupting means.

25 2. A progressive contact maker comprising contact points divided into groups or sets, a plurality of groups of circuits in which said contacts are connected, a normally rotating trailer-arm adapted to make contact with the contact points of one group at one time, means for interrupting the rotation of the trailer arm, and means, independent of the 30 circuits containing the contact points, for controlling the interrupting means.

35 3. The combination with a series of lines, of a terminal clip for each of the lines, a contact point for each of the terminal clips, both clips and points being divided into groups or sets, of a normally rotating contact-maker adapted to make contact with the contact points of one group or set at one time, by the relative movement between said contact maker and points, means for interrupting 40 the rotation of the contact maker, and means controlled by the lines for operating the interrupting means.

45 4. The combination with a series of lines, of a terminal clip for each of the lines, a contact point for each of the terminal clips, both clips and points being divided into groups or sets, of a contact maker adapted to make contact with the contact points of one group or set at one time, by the relative movement 50 between said contact maker and points, means for temporarily holding said contact maker on said contact points, and means, controlled by the lines and independent of the circuit containing the contact points, for controlling said holding means.

55 5. The combination with a series of line terminals arranged in groups or sets, electro-magnetic means for each group of line terminals, a normally rotating contact-maker adapted to establish electrical connection with said group of terminals, and means for stopping said contact maker, said means being controlled by said electro-magnetic means.

60 6. In an electrical system, means for se-

lecting and identifying any one of a plurality of circuits which consists of a plurality of sets of elements, with extension circuits or branches extending between them less in number than the total number of circuits to 70 be served, each element of the first set adapted when actuated to select and connect to the extensions all of its group of circuits, and each element of the second set adapted when actuated to select and render operative a 75 single unit out of the group, corresponding to the circuit to be selected.

7. In an electrical system, means for selecting and identifying any one of a plurality of circuits which consists of a rotating circuit 80 changer, a plurality of sets of controlling elements, with extension circuits or branches extending between them less in number than the total number of circuits to be served, each element of the first set adapted when 85 actuated to cause the circuit changer to select and connect to the extensions all of its group of circuits, and each element of the second set adapted when actuated to select and render operative a single unit out of the 90 group, corresponding to the circuit to be selected.

8. The combination with a series of line terminals divided into groups or sets and a series of normally open local circuits, one for 95 each line terminal, of means controlled by the groups adapted to partially close one of said local circuits, and means controlled by one component in this group for completing said local circuit.

100 9. In an electrical system of communication, the combination of the following instrumentalities: a central station, a plurality of sending apparatuses, line circuits connecting the same to the central station, and a circuit changing device at the central station comprising primary and secondary controlling means, together with branch circuit connections between the same and from the circuit changer to line identifying circuits, said 110 primary controlling means adapted in response to a call over an individual line to render inoperative an inactive portion of the line circuits, and the secondary controlling means adapted to render inoperative an inactive portion of the remaining circuits, and 115 to complete the connection to its identifying circuit.

10. In an electrical system of communication, the combination of the following instrumentalities: a central station, a plurality of sending apparatuses, line circuits connecting the same to the central station, and a circuit changing device at the central station comprising primary and secondary controlling 125 means, together with branch circuit connections between the same and from the circuit changer to line identifying circuits, said primary controlling means adapted in response to a call over an individual line to 130

render inoperative all the line and branch circuits except the group containing the calling line, and the secondary controlling means adapted to render inoperative all of the circuits of the group except the one calling, and to complete the connection to its identifying circuit.

11. In an electrical system of communication, the combination of the following instrumentalities: a central station, a plurality of substations with circuit controlling devices, line circuits interconnecting them, a circuit changing device at the central station comprising primary and secondary elements, and branch extension circuits less in number than the number of lines extending between said elements, said line circuits divided into groups, and having corresponding group contacts in the said primary element, a controlling magnet for the primary element for each group, adapted to be energized over any line in the group, controlling magnets for the secondary element, one corresponding to each unit in a single group in the primary element, means to segregate the individual lines upon the operation of the circuit changing device, and line identifying or controlling means associated with said circuit changing

device and adapted to be selectively operated by the elimination of circuit groups and circuit units in the primary and secondary elements respectively.

12. A plurality of electric circuits divided into groups, a normally open branch circuit for each of said circuits, a primary circuit-controlling device for each of said groups normally subject to control by any of the circuits of its respective group, a switching device controlled by said circuit-controlling devices to partially close all the branch circuits of the respective groups, one or more secondary circuit closing devices adapted to completely close any one of the branch circuits partially closed, and a circuit interrupter adapted to place all the primary circuit-controlling devices beyond the control of the said plurality of electrical circuits.

In testimony whereof I have hereunto set my hand at New York, in the county and State of New York this thirtieth day of 50 March, nineteen hundred and four.

ERNEST A. FALLER.
